F. DUTCHER.
RAILWAY SIGNAL TORPEDO.
APPLICATION FILED APR. 4, 1912.

1,102,888.

Patented July 7, 1914.

UNITED STATES PATENT OFFICE.

FRANK DUTCHER, OF VERSAILLES, PENNSYLVANIA, ASSIGNOR TO CENTRAL RAIL-WAY SIGNAL COMPANY, OF PITTSBURGH, PENNSYLVANIA, A CORPORATION OF NEW JERSEY.

RAILWAY SIGNAL-TORPEDO.

1,102,838.

Specification of Letters Patent.

Patented July 7, 1914.

Application filed April 4, 1912. Serial No. 688,573.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes, and it comprises a paper explosive containing case and a metallic foil covering for the case, which has integral folded extended ends projecting 15 and constituting rail engaging straps.

The object of my present invention is to provide an improved manner of inclosing a paper explosive inclosing case within an elongated metallic sheet and cementing the 20 edges of the sheet, the folded sheet adapted to have its ends act as rail-engaging members for attaching the torpedo to a railway rail.

In the accompanying drawings—Figure 1 is a perspective view of an improved torpedo, showing it in position on a railway rail. Fig. 2 is a detached perspective view of the sheet metal foil blank, the dotted lines indicating the bends of the longitudinal folds. Fig. 3 is a perspective view showing the manner of applying the covering to the explosive containing case. Fig. 4 is a perspective view showing the first folds which are made in the sheet. Fig. 5 is a perspective view showing the edge or 35 inwardly extending edge folds beyond the explosive containing case. Fig. 6 is a view showing the manner of compressing the folded ends of Fig. 5.

40 In carrying out my invention, I provide a rectangular open ended tubular paper case 1, (dotted lines, Fig. 3) which is adapted to receive and hold an explosive compound (not shown). An elongated metallic sheet foil blank 2 is provided and upon which is placed the case 1, at the center of the blank. The blank 2 is then folded up on the two inner lines 3, into substantially a trough or U-shape, as shown in

Fig. 3. When in this shape the case 1 is placed in the trough between its ends, and will be properly centered by two members 4. These members 4 have the same cross-sectional shape as the case 1, and while these members are in the position shown in Fig. 1, the side wall 5 of the sheet trough is doubled down on the case and the members 4 to the position shown in Fig. 4. The other wall 6 of the trough-shaped sheet is doubled over the wall 5, a waterproof elastic cement 7 having been placed so as to cement the overlapping edges of the walls 5 and 6. As here shown, the cement 7 is placed on the inner side of the wall 6. The members 4 are then withdrawn, leaving an elongated metallic box-shaped member holding the case 1 therein. The edges 8 of the extended ends of these box-shaped members are then folded in, as shown at 9, forming bellows-like folds, increasing in width from the ends of the case to the ends of the folded sheet. These folded ends 10 are then compressed substantially equal distances toward a longitudinal line drawn through the center of the case, thus compressing the folded ends 10, as shown in Fig. 6, and thus forming the extended folded compressed ends 11 into railway rail-engaging members adapted to be bent around the railway rail 12, as shown in Fig. 1. By folding the sides 8 of the extended tabular portions inward into bellows-like folds as described, the extended ends are made up with longitudinally extending portions having four thicknesses of metal, the object of which is to increase the strength and durability of the rail-engaging members 11, and by the increased thickness, enables the members 11 to better resist being moved off after they have been bent around the railway rail, as shown in Fig. 2.

The metallic sheet or foil 2 is composed of aluminum, whereby it is very durable, light and capable of withstanding the severest use to which it would be subjected in the hands of railroad men and is of a nature to remain in the shape in which it is bent to hold the torpedo in position on the rail.

Having thus described my invention what

I claim and desire to secure by Letters Patent is:

A railway signal torpedo, comprising a paper explosive containing case, a metallic sheet covering wrapped around the case and having its ends projecting beyond the case to form rail-engaging members, the edges of the extensions pressed inward into bellows-like folds which increase in width from the

ends of the case to the ends of the extensions for the purpose described.

In testimony whereof I hereunto affix my signature in the presence of two witnesses.

FRANK DUTCHER.
